UNITED STATES PATENT OFFICE.

CECIL MUNRO DYER, OF KEW, MELBOURNE, VICTORIA, AUSTRALIA.

STARTER FOR INTERNAL-COMBUSTION ENGINES.

1,396,736.

Specification of Letters Patent.

Patented Nov. 15, 1921.

Application filed January 17, 1920. Serial No. 352,050.

To all whom it may concern:

Be it known that I, CECIL MUNRO DYER, a subject of the King of Great Britain, and residing at Narbethong, 30 Barrington avenue, Kew, Melbourne, in the State of Victoria, Australia, have invented certain new and useful Improvements in Starters for Internal-Combustion Engines, of which the following is a specification.

This invention relates to devices for making a rich mixture for starting purposes in internal combustion engines. It is the object of the present invention to provide a form of auxiliary carbureter which is only intended to be used for starting purposes or in case of emergencies, this carbureter being relied upon entirely to provide the mixture for starting, while the normal running carbureter is cut out of action. The starting carbureter is then designed so as to give a rich but uniform mixture in which the fuel is properly vaporized, and for this purpose the carbureter is constructed as hereinafter set forth with reference to the accompanying drawings, wherein:

Figure 1 shows the device in side elevation.

Fig. 2 shows it in end elevation.

Fig. 3 shows the device in partial longitudinal section.

A central hollow stem 1 is used having a thin disk 2 at its end in which one or more holes are drilled according to the size of the engine and the amount of fuel required.

The base 5 of the stem fits into the end of a sleeve or socket 3 and is clamped in position by a nut 4. The socket 3 is formed with two holes therein marked 6 and 7 which coöperate with a hole at 8 in a revolute sleeve 9 surrounding the socket 3. The end of the socket 3 is formed as a nut 10 with a projecting hollow stem which is threaded at 11 to engage in the wall of an induction pipe 13, the projecting end being

perforated as at 12 to allow of the escape of the rich mixture into the induction pipe. The sleeve 9 has an arm 14 projecting therefrom to which an operating rod is connected at 15, whereby the sleeve can be turned in either direction.

In the construction shown the supply of fuel to the device is automatically controlled by the movement of the arm 14 and sleeve 9. 16 is a cock controlling the supply of liquid fuel from pipe 17 communicating with any suitable source of supply. The

union 18 connects the cock 16 with the projecting face of the hollow stem 1. The arm 19 of the cock engages in a slot in the lever 20 projecting from the sleeve 9. 60

In operation, assuming the engine to be running, the cock 16 will be closed and the hole 8 in the sleeve 9 will be opposite the blank wall of the socket 3 between the two holes 6 and 7. For starting purposes the 65 arm 15 is pulled forward causing the hole 8 to register with the hole or slot 6, while the slotted arm 20 engaging the arm 19 of cock 16 turns this latter to admit liquid fuel to the hollow stem 1. The suction in 70 the induction pipe 13 causes air to be drawn out through the holes 12, and the rush of air entering the registering holes 8 and 6 past the end of the stem 1 draws out fuel through the perforated end 2 of the stem, 75 so that the rich mixture is supplied to the induction pipe. In order to assist in vaporizing this mixture a roll of wire gauze 21 or the like may be fitted in the perforated end of the socket member as shown in Fig. 3. 80 When the engine picks up on the normal carbureter the starting device is thrown out of action by pushing back the arm 14 until the hole 8 is returned to the position of Fig. 1. In order to allow of the drawing 85 in of air without fuel through this device, to exert a braking action for instance to retard the engine when running down hill, the arm 14 is moved further while the cock 16 remains closed, until the hole 8 registers 90 with the hole 7. This admits air through the socket into the induction pipe.

It will be obvious that the device as above described can be used as a stand-by or auxiliary carbureter in the event of defective working of the normal carbureter, or where the latter becomes inoperative on account of a choked up petrol pipe, for instance.

I claim:

1. A priming and starting device for internal combustion engines, comprising a tubular socket member having a hollow perforated extension adapted to be fitted to an induction pipe and to project into the same, 105 a stem member fitting into said tubular socket and formed with a perforation at its end for the egress of fuel, means for supplying liquid fuel to said stem member and means for rigidly securing said stem member 110 in the socket member, and a sleeve adapted to turn upon the socket member, with means

for operating said sleeve, the sleeve and socket member having perforations therein which can be brought into and out of register by such turning movement.

- 5 2. A priming and starting device for internal combustion engines, comprising a tubular socket member having a hollow perforated extension adapted to be fitted to an induction pipe and to project into the same,
- 10 10 a stem member fitting into said tubular socket and formed with a perforation at its end for the egress of fuel, means for rigidly securing said stem member in the socket member, a cock connected to said stem member, means for supplying liquid fuel through said cock, a sleeve adapted to turn upon the socket member, with means for operating said sleeve, the sleeve and socket member having perforations therein which can be
- 15 20 brought into and out of register by such turning movement, and interconnecting means between said sleeve and cock for cutting off the fuel supply when the device is thrown out of action.

- 25 3. A priming and starting device for in-

ternal combustion engines, comprising a socket having a hollow end adapted to be fitted to an induction pipe and to project into the same, said end being perforated, a stem member fitting into said socket and formed with a perforation at its end for the egress of fuel, means for securing said stem member in the socket member, a cock connected to said stem member, means for supplying liquid fuel through said cock, a sleeve adapted to turn upon the socket member, with means for operating said sleeve, one of the said sleeve and socket members having two apertures therein adapted to be brought into and out of register with an aperture formed on the other member on turning said sleeve, and interconnecting means between said sleeve and cock so proportioned that when one of the said two apertures is in register with the said single aperture the cock is in the open position, while when the sleeve is turned further the cock is in the shut position.

CECIL MUNRO DYER.
